UNITED STATES PATENT OFFICE.

RANSOM SABIN, OF SHELBY, MICHIGAN.

PORTABLE PANTRY.

SPECIFICATION forming part of Letters Patent No. 448,372, dated March 17, 1891.

Application filed October 19, 1889. Serial No. 327,517. (No model.)

To all whom it may concern:

Be it known that I, RANSOM SABIN, a citizen of the United States, residing at Shelby, in the county of Oceana and State of Michigan, 5 have invented a new and useful Portable Pantry, of which the following is a specification.

The invention relates to portable pantries.

The object of the present invention is to 10 provide a portable pantry of simple and inexpensive construction capable of containing all the articles necessary for a complete pantry.

The invention consists in the construction 15 and novel combination of parts hereinafter described, illustrated in the accompanying drawings, and pointed in the claims hereto appended.

In the drawings, Figure 1 is a perspective 20 view of a portable pantry constructed in accordance with the invention. Fig. 2 is a central vertical transverse sectional view. Fig. 3 is a vertical longitudinal sectional view. Fig. 4 is a detail perspective view of the refrigerator-pan. Fig. 5 is a similar view of the 25 revolving spice-box. Fig. 6 is a detail view showing the manner of journaling the combined bread-board and door. Fig. 7 is a detail view illustrating the manner of securing 30 the spring-actuated journals.

Referring to the accompanying drawings by letter, A designates the frame, which is divided by an approximately central parting-strip A' into an upper and lower portion. 35 The upper half of the pantry is divided by two partitions A² into a central section and two side sections. Each side section has a hinged door B and two shelves b and b', which occupy the upper portion and leave a lower 40 space b², in which is pivotally mounted a bin C, whose lower front end is curved and whose upper end is provided with a handle c', by means of which the bin is tilted to expose its open upper end to permit access to its contents. The journals c² of the bin C find bearings in inclined slots d of side pieces D, and the inclined slots have their upper ends open to enable the bin to be removed from the pantry. The inclined slots may be made in the 45 side pieces D, as described, or similar grooves can be made in the partitions A² and the sides

of the frame A, which grooves will answer the same purpose as the slots d.

The central section of the upper half of the pantry is provided with a shelf a, which divides the section which is provided beneath the shelf with a number of drawers, and is subdivided above the shelf a by shelves a' a². Between the shelves a' and a² is pivoted a rotary spice-box E, which is composed of two 50 disks or octagonal plates e e', which are secured together by radial partitions e², which form spaces adapted to receive segmental drawers or boxes e³, and drawers F are provided at each side of the spice-box E. Between the shelf a and the shelf a² are secured partitions a⁴, which are provided with inclined slots a⁵, that are adapted to receive the ends or handles of a rolling-pin G. The rolling-pin lies about midway between the shelves 55 a and a², and below the rolling-pin is arranged a meat-board H. The upper portion of the central section is closed by doors I, which are hinged to the partition A², and the lower portion is closed by a combined bread-board and 60 door J. The sides of the door are provided near the lower end with recesses j, in which are arranged spring-actuated journals j', which are retained in the recesses by slotted plates j². The outer ends of the journals j' 65 are reduced and beveled, and form shoulders which bear against the slotted plates j² and prevent the springs j³ forcing the journals out of the recesses. The partitions A² are provided near their lower front edges with plates 70 having circular bearing-recesses a⁶, which have communicating with them grooves a⁷, whose bottoms are beveled or inclined, whereby when the spring-actuated journals j' are brought opposite the grooves a⁷ they may 75 be forced in said grooves, and thereby cause the inclined or beveled bottoms to depress the spring-actuated journals and enable the bread-board to be removed from its bearing. The lower half of the pantry is also divided 80 by partitions A² into three sections or compartments, which are closed by hinged doors K and K'. The outer compartments are provided with pivoted bins L, which are constructed and mounted similarly to the bin C, 85 heretofore described, and the central compartment and door K' are provided with a lin- 90 95 100

ing of galvanized iron or similar sheet metal M, which forms a dead-air space to serve as a non-conductor of heat and cold and adapt the central compartment to perform the function of a refrigerator. The partitions A³ are provided on their sides, which form the walls of the center compartments, with curved strips N, that are adapted to support a refrigerator-pan O, whose bottom o' is curved, and 10 has its ends o² rolled. The sides o³, o⁴, o⁵, and o⁶ are soldered or similarly secured to the curved bottom o' and form a pan adapted to receive ice. The pan is provided with a depending tube P, which extends below the 15 upper edges of a tank Q, that is secured to one of the partitions A³, and has communicating with it a drain-pipe R, that is also secured to the partition A³, and extends along the same to the bottom of the pantry, near 20 the front thereof, to permit the escape of the water, which is designed to be received by some suitable vessel. The bottom o' extends beyond the sides o³ and o⁴, and is provided with perforations o⁷ to permit the air, after it 25 has been cooled, to descend and be replaced by warmer air.

From the foregoing description and the accompanying drawings the construction, operation, and advantages of the invention will 30 readily be seen; and I desire it to be understood that I do not limit myself to the precise details of construction herein shown and described, as I may without departing from the spirit of the invention make various minor 35 changes therein.

Having thus described my invention, what I claim is—

1. The combination, in a portable pantry, of

the partitions A², provided with recesses a⁶, forming bearings and grooves a⁷ communicating with said recesses, and the combined bread-board and door provided with spring-actuated journals adapted to engage said recesses and be removed therefrom, substantially as described. 40

2. The combination, in a portable pantry, of the partitions A², provided with recesses a⁶ and grooves a⁷, the combined bread-board and door having recesses, the spring-actuated journals having their ends beveled and adapted to engage said recesses a⁶ and to be removed therefrom, and the slotted plate retaining the spring-actuated journal in the recesses of the combined bread-board and door, substantially as described. 45

3. The combination, in a portable pantry, of the partitions A³, the curved strips secured to the partitions, a refrigerator-pan resting on said strips and comprising the curved bottom, having its front and rear ends rolled and being provided with a depending tube, the sides secured to said bottom and having the front one bent over and secured to the outside of the bottom to provide a suitable hand-hold, the sides of said bottom projecting beyond 60 the sides of the pan and being provided with perforations, and a suitable drain-pipe, substantially as described. 65

In testimony that I claim the foregoing as my own I have hereto affixed my signature in 70 presence of two witnesses.

RANSOM SABIN.
